Application February 22, 1944, Serial No. 523,416

4 Claims. (Cl. 102—49)

1

This invention relates to reaction propulsion devices of the so-called "rocket type," more particularly to an improved arrangement for supporting the propelling charge.

It has been proposed heretofore to provide a propelling charge of slow-burning powder, or other suitable combustible material, in the form of annular sticks and to support such sticks by means of a cage comprised of a plurality of rod-like elements and end plates, such as shown in the copending application, Serial No. 487,689, of Warren H. Farr, filed May 20, 1943.

The present invention has for its object the provision of relatively simple means for rigidifying the above-mentioned cage structure to the end that such rigidification will aid in maintaining the cage structure coaxial with the projectile whereby to aid in insuring true flight of the projectile.

Another object is to provide such a cage structure with improved means of economical manufacture for locking the rod-like members against vibration and substantial deflection.

With the above and other objects in view which will be apparent from the following description to those skilled in the art to which the invention appertains, the present invention consists in certain features of construction and combinations of parts to be hereinafter described with reference to the accompanying drawings, and then claimed.

In the drawings which illustrate suitable embodiments of the present invention:

Figure 1 is a longitudinal section through a rocket projectile having the arrangement of the present invention incorporated therein;

Figures 2 and 3 are enlarged transverse sections taken substantially on the lines 2—2 and 3—3, respectively;

Figure 4 is an enlarged side elevation of the cage for the propelling charge in partially assembled condition;

Figures 5 and 6 are transverse sections taken substantially on lines 5—5 and 6—6, respectively, of Figure 4;

Figure 7 is a fragmentary longitudinal section of a rocket projectile similar to that of Figure 1 but in which the burster tube is not used and showing the arrangement employed to compensate for the non-use of the burster tube, and

Figure 8 is an enlarged transverse section taken substantially on the line 8—8 of Figure 7.

Referring to the accompanying drawings in which like numerals refer to like parts throughout the several views, there is shown in Figure 1 for the purpose of illustration, one form of pro-

2

jectile which embodies a main projectile body 10 having a chamber 11 therein for the reception of an explosive charge, not shown, and having an axially and rearwardly extending burster tube 12.

Threadably secured to the base end of the body 10 and extending rearwardly therefrom is a tubular casing 13 having its trailing end contoured to form an axially opening Venturi passage 14. Suitable stabilizing fins 15 are pivoted at 16 to a ring 17 which is externally threaded to the trailing end of the casing 13.

Referring to Figure 1, it will be noted that the casing 13 is provided at its forward end with an internal shoulder 18. This shoulder, as will be later described, forms a support for the cage 19 which carries the propelling charge.

The cage 19 includes, as shown in Figures 1 to 6, a plurality of longitudinally extending rods 20, an annular rearward end plate 21 and an annular forward end plate 22, the plates 21 and 22 having inner annular flanges 23 and 24 respectively. Each of the rods 20 is provided with integral upset or bulbous portions 25 and 26 intermediate its ends and with upset heads 27 at its opposite ends. The rods 20 extend through the rearward end plate 21 in uniformly circumferentially spaced relation, the heads 27 at the rearward ends seating against the plate 21. Such upset heads 27 are formed after the rods 20 are extended through the plate 21.

The propelling charge is in the form of annular sticks 28 of slow burning powder or other suitable material, the openings 29 therein being slightly larger than the heads 27 and upset portions 25 and 26 to permit the sticks to be slipped over the rods.

The forward end plate 22 is provided with uniformly circumferentially spaced keyhole slots 30, the enlarged portions of the slots 30 being of sufficient diameter to permit the head portions 27 of the rods 20 to be slipped therethrough. In the assembled condition, it will be noted that the rods 20, as shown in Figure 2, are disposed in the narrower portions of the slots 30.

Adjacent the upset portions 25 are a pair of annular rigidifying plates 31 and 32, which may be in the form of metal stampings, the plate 31 having radial slots 33 extending outwardly from the inner periphery thereof and the plate 32 having radial slots 34 extending inwardly from the outer periphery thereof. The slots 33 and 34 have the same circumferential spacing as the rods 20 and the rods extend through these slots. The plates 31 and 32 abut each other and in their

assembled relation lock the rods 20 against radially inward and outward movement.

Similar plates 35 and 36 are associated with the rods 20 adjacent the upset portions 26.

The sticks 28 comprising the propelling charge are supported on the rods 20 in series, there being one series between the plate 32 and the end plate 21, a second series between the plates 31 and 36 and a third series between the plate 36 and the forward end plate 22. It is obvious that any desired number of such series may be employed, depending on the length of the casing 13.

The complete cage assembly including the sticks 28 is supported within the casing 13, the forward end plate 22 seating against the shoulder 18. An annular groove 37 is provided in the base end of the body 10 for the reception of the heads 27 at the forward ends of the rods 20. The cage assembly, of course, is disposed within the casing 13 before the casing and main body portion 10 are assembled.

As will be seen from Figure 1, the burster tube 12 extends axially within and through the cage assembly just described. In order to stabilize the rearward end of the cage assembly and maintain it against lateral movement, a number of ears 38 are struck from the flange 23 of the rearward end plate 21 into the plane of the plate 21 so that such ears will seat against the burster tube 12, as shown in Figures 1 and 3, and thus support the cage assembly against lateral deflection.

In some cases, the burster tube 12 may be omitted, and in this case, as shown in Figures 7 and 8, the rearward end plate 21 is formed with radially outwardly extending projections 38-a which are arranged to engage with the inner wall surface of the casing 13 and thus, in this manner, support the cage assembly against lateral deflection. Apart from this the construction is generally the same as that of Figure 1.

In the assembly of the cage, prior to the assembly of the plates 31 and 32, the lower series of charge sticks 28 are slipped over the rods 20 to a position between the rearward end plate 21 and the upset or bulbous portions 25. Then the rods 20 are distorted to an outward position, as shown in broken outline in Figure 5, whereby the plate 32 is inserted within the circumferentially spaced rods 20. The rods 20 are then moved radially back to a normal position within the slots 34. Next, the rods 20 are distorted radially inwardly, as shown in broken outline in Figure 6, and the plate 31 is slipped into surrounding relation with respect to the rods 20 with the slots 33 aligned with the rods. After the plate 31 clears the bulbous portions 25, the rods are allowed to spring back outwardly into the slots 33. The plate 31 is then slid along the rods into engagement with the plate 32, thus closely confining the rods in the opposed slots 33 and 34 and holding them against relative radially inward or outward movement.

The second series of charge sticks 28 is then assembled to the rods 20 and the plates 35 and 36 are assembled in the same manner as the plates 31 and 32.

After the third or forward series of charge sticks 28 is assembled to the ends of the rods 20, the rods are again sprung radially outwardly to permit the forward end plate 22 to be slipped over the end heads 27, the heads extending through the enlarged portions of the slots 39. The rods are then allowed to spring back into the narrower portions of the slots 30.

There is thus provided a relatively simple ar-

rangement for supporting the propelling charge, the plates 31-32 and 35-36 rigidly holding the rods against lateral deflection or vibration and the ears 38 in the one case and the extending portions 38-a in the other case holding the rearward end against lateral movement. The construction described is particularly advantageous in that there is no likelihood of the cage assembly becoming distorted or shifted to an off-center position during flight of the projectile. As a result the projectile will have a truer flight than has been the case heretofore.

Another important advantage of the construction described resides in the fact that by rigidifying the charge supporting cage, the charge sticks are prevented from breaking down through contact with the walls of the casing or the burster tube incident to vibration or deflection of the cage rods. Such breaking down of the charge sticks is extremely disadvantageous in that small pieces of the charge may exhaust through the Venturi passage and cause the projectile to deviate from its intended flight or cause serious personal or property damage when the projectile is fired from its projector.

The arrangement described also permits free flow of the products of combustion between and around the series of charge sticks.

It will be obvious to those skilled in the art that various changes may be made in the detailed construction and arrangement of the parts described, without departing from the spirit and substance of the invention, the scope of which is defined by the appended claims.

What is claimed is:

1. A device for supporting annular charges of combustible material for use in rocket projectiles, comprising a pair of spaced coaxial annular end plates, a plurality of parallel rod-like elements extending between and supported by said end plates in circumferentially spaced relation with respect to each other, means intermediate said end plates for locking said rod-like elements against lateral movement, said means including a pair of annular abutting plates, the one surrounding said elements and having radial recesses in its inner periphery and the other being surrounded by said rod-like elements and having radial recesses in its outer periphery, said rod-like elements being seated in said recesses of both said plates and said recesses being of such width as to closely engage and thereby confine said rod-like elements against lateral movement, said rod-like elements being arranged to support the annular charges of combustible material between said end plates and said intermediate plates.

2. In a rocket device having a tubular casing and a coaxial central member circumferentially spaced from the inner wall surface of said casing, an annular cage-like member within said casing and surrounding said central member, said cage-like member comprising a pair of end elements and a plurality of longitudinally extending parallel rods carried by said end elements in circumferentially spaced relation about a common axis, one of said end elements being supported by said casing and the other of said end elements having a plurality of radially inwardly extending portions seating against said central member, said end elements holding said cage-like member against lateral movement relative to said casing, and annular elements of combustible material surrounding and supported by said rods.

3. In a rocket device having a tubular casing, a

cage-like member for supporting annular elements of combustible material within said casing comprising a pair of annular end rings in spaced apart relation and a plurality of generally parallel rods carried by said end rings in circumferentially spaced relation about a common axis, and a plurality of annular cylinders of combustible material surrounding said rods, one of said end rings being supported at one end of said casing and the other of said end rings having circumferentially spaced radially outwardly extending portions engaged with the inner wall surface of said casing for holding said cage-like member coaxially within said casing.

4. In a reaction propulsion device having a 15 tubular casing, a cage for holding a propelling charge within said casing, comprising spaced end members, longitudinally extending rods carried

by said end members in circumferentially spaced relation about a common axis, and at least one pair of closely adjacent annular members intermediate the ends of said rods, one of said annular members being disposed within the circle of rods and having radial recesses at its outer periphery partially closely surrounding said rods from one side thereof, and the other of said annular members surrounding the circle of rods and having radial recesses at its inner periphery partially closely surrounding said rods from the other side thereof, said end members having radial portions holding the opposite ends of said cage against movement laterally of said casing, and annular elements of combustible material at opposite sides of said pair of annular members and surrounding said rods.
